UNITED STATES PATENT OFFICE.

CLAUDIUS DORNIER, OF FRIEDRICHSHAFEN, GERMANY, ASSIGNOR TO ZEPPELIN-WERKE LINDAU, GESELLSCHAFT MIT BESCHRANKTER HAFTUNG, OF LINDAU-REUTIN, GERMANY, A GERMAN CORPORATION.

FLYING-MACHINE COVER.

1,427,448.

Specification of Letters Patent. Patented Aug. 29, 1922.

Application filed March 31, 1921. Serial No. 457,541.

To all whom it may concern:

Be it known that I, CLAUDIUS DORNIER, a citizen of Germany, residing at Friedrichshafen, Germany, have invented certain new and useful Improvements in Flying-Machine Covers (for which I have filed an application in Germany on December 1, 1919), of which the following is a specification.

My invention relates to flying machines and more especially to a protection for the supporting surfaces of such machines, having for its object to protect in particular the covering thereof against the influence of the weather. To this end, there are arranged to either side of the hull readily detachable protective coverings, capable of being rolled up, and which suitably shaped and dimensioned will reliably protect the supporting surfaces to a greater or less extent against the action of the weather. Preferably the said covering which may consist of waterproof canvas or the like is provided at various points with fastenings.

In the drawings affixed to this specification and forming part thereof a flying machine embodying my invention is illustrated by way of example. In the drawing

Fig. 1 is a front view and

Fig. 2 a plan view.

Referring to the drawing, to the right and left of the hull 1 there is arranged above each of the two supporting surfaces 2 a rolled-up covering 3, which when unrolled and spread out assumes the position 3¹. The two coverings are joined at their ends, and

this at the underside in the centre of the machine, by means of eyes 4 and cords 5. A strip 6 of the supporting surface may be trod on in order to facilitate the rolling up and unrolling, respectively, of the covering. At 7 there are arranged small studs on which the covering may be hooked by means of eyes.

In certain cases it may prove fully sufficient to only cover the upper surface and to attach the two coverings, which extend somewhat beyond the ends of the wings, by means of cords or eyes relatively to the supporting surface or some other portion of the machine.

I claim:

1. In a flying machine in combination, a pair of supporting surfaces and a pair of covers, adapted to be rolled up, attached with one end to the supporting surface bases.

2. In a flying machine in combination, a pair of supporting surfaces, adapted to be trod on and a pair of covers, adapted to be rolled up, attached with one end to the supporting surface bases.

3. In a flying machine in combination, a pair of supporting surfaces, a pair of covers, adapted to be rolled up, attached with one end to the supporting surface bases and means for fastening said coverings to said surfaces.

In testimony whereof I affix my signature.

CLAUDIUS DORNIER.
